(57) **CLAIM**

The ornamental design for a portion of display panel or screen with animated graphical user interface, as shown and described.

DESCRIPTION

FIG. 1 is a front view of a first embodiment of a portion of a display panel or screen with animated graphical user interface showing a first image in a sequence of my new design;

FIG. 2 is a second image thereof;

FIG. 3 is a third image thereof;

FIG. 4 is a fourth image thereof;

FIG. 5 is a fifth image thereof; and

FIG. 6 is a sixth image thereof.

FIG. 7 is a front view of a second embodiment of a portion of a display panel or screen with animated graphical user interface showing a first image in a sequence of my new design;

FIG. 8 is a second image thereof;

FIG. 9 is a third image thereof; and

FIG. 10 is a fourth image thereof.

FIG. 11 is a front view of a third embodiment of a portion of a display panel or screen with animated graphical user interface showing a first image in a sequence of my new design;

FIG. 12 is a second image thereof;

FIG. 13 is a third image thereof;

FIG. 14 is a fourth image thereof;

FIG. 15 is a fifth image thereof; and

FIG. 16 is a sixth image thereof.

The appearance of an image sequentially transitions to another between FIGS. 1-6, FIGS. 7-10, and FIGS. 11-16, respectively. The process or period in which an image transitions to another forms no part of the claimed design. The outermost broken lines showing a portion of the display panel or screen and form no part of the claimed design. The broken lines within the outermost broken lines illustrate a portion of an animated image that forms no part of the
